(57) **CLAIM**

The ornamental design for a mobile pill purse, as shown and described.

DESCRIPTION

FIG. 1 is a top isometric view of the mobile pill purse shown in a closed position;

FIG. 2 is a top isometric view, with the security flap in the open position using “hook and pile” or other attachment means in the open position to accept and maintain possession of items placed therein.

FIG. 3 is a bottom isometric view, showing the retention mechanism using “hook and pile” or other attachment means in the open position; and,

FIG. 4 is a bottom isometric view, showing a garment retention strap in the closed position when applied to a wearer’s clothing.
